UNITED STATES PATENT OFFICE

154,061

DESIGN FOR A FINGER RING

James S. Patty, New York, N. Y.

Application October 6, 1948, Serial No. 148,981

Term of patent 3½ years

(Cl. D45—10)

To all whom it may concern:

Be it known that I, James S. Patty, a citizen of the United States of America, residing in New York city, county of New York, and State of New York, have invented a new, original, and ornamental Design for a Finger Ring, of which the following is a specification, reference being had to the accompanying drawing, forming part thereof, wherein:

Figure 1 is a front elevational view of a finger ring showing my new design.

Figure 2 is a right side elevational view.

Figure 3 is a top plan view, and

Figure 4 is a left side elevational view.

I claim:

The ornamental design for a finger ring, substantially as shown.

JAMES S. PATTY.
